UNITED STATES PATENT OFFICE.

ZYGMUNT H. PEHEL, OF NEW YORK, N. Y.

LOCK-OPERATED CIRCUIT-CLOSER.

1,388,119.

Specification of Letters Patent. Patented Aug. 16, 1921.

Application filed September 16, 1919. Serial No. 324,115.

To all whom it may concern:

Be it known that I, ZYGMUNT H. PEHEL, a citizen of Poland, and a resident of the city of New York, borough of Manhattan, county of New York, and State of New York, have invented a new and Improved Lock-Operated Circuit-Closer, of which the following is a full, clear, and exact description.

10 This invention relates to locks, and particularly to a burglar proof lock to be used in connection with a burglar alarm such as a bell.

An object of the invention is to provide 15 a simplified form of lock which is positive in its locking function, and which will open only through proper manipulation of the owner's key. It is a purpose to provide a lock operable in connection with a burglar alarm system which will ring a bell in case a key, other than the owner's key, is inserted 20 in the lock with the attempt to open the door on which the lock is installed; and it is also a purpose to provide a lock with a 25 switch which will close an electric circuit and ring the alarm bell in case a burglar attempts to jimmy the door or open the door by prying on the face of the lock by a tool inserted between the door facing and the 30 lock.

I have in view the provision of an electric signal such as a bell to be connected with this door lock and so arranged that the bell will ring even though the owner's key, or 35 any other key, is inserted in the lock with the attempt to force an opening through the door.

The present invention relates to a burglar 40 alarm system operable in connection with a form of lock as disclosed in my application for patent filed June 13, 1919, under the Serial No. 304014, and which application was allowed on July 15, 1919, #1,330,650.

With the above principal objects in view 45 and others, the invention has relation to a certain burglar alarm system used in combination with a lock as set forth in the appended claims, as described in this specification, and as portrayed in the accompanying drawings, wherein:

Figure 1 shows the lock, and a burglar 50 alarm such as a bell is shown in diagrammatic form connected with the lock. This view illustrates the lock in normally locked 55 position with the burglar alarm quiescent.

Fig. 2 illustrates the lock in locked position with a key inserted therein and rotated in a manner to unlock said lock. In this view the locked parts are shown in a position which closes the circuit through the 60 burglar alarm system to ring the bell, and a key as shown inserted in the lock.

A burglar alarm system and lock constructed in accordance with this invention comprises a bolt actuated by a rack and 65 pinion. A key is used to actuate the pinion, and a pawl is pivoted on the pinion to close the key receptacle to prevent insertion of said key into a socket formed in the pinion. An electric switch is mounted adjacent the 70 pawl and is impinged by the pawl when a key is inserted to unlock the lock. This action on the part of the pawl closes an electric circuit to ring a bell. A contact device is also provided on the lock and included in 75 parallel with the alarm or bell circuit to ring the alarm in case a burglar attempts to force the door with a jimmy or by prying between the door lock and door facing.

The above is a general synopsis of my invention, and I will now proceed to disclose 80 same in detail by particularly referring to the drawings to point out parts therein.

Referring to the drawings there is shown 85 a lock casing 5 open on the front face thereof to disclose operating parts. The casing is provided with a guide loop 6, and a lock bolt 7 is slidably confined in the guide loop and casing. A rack 8 is fixed to the bolt, and is slideable back and forth in a guide 90 10, said guide 10 being mounted on the casing 5.

A pinion 12 is rotatably mounted in the lock casing and meshes with the gear rack 8. The pinion is provided with key receptacles 13. Two key receptacles are usually sufficient and are formed diametrically opposite one from the other in the pinion 12 so that corresponding projections of a key may be inserted in the holes of receptacles 95 13 in order to rotate the pinion. The pinion 12 is provided on the periphery thereof with a shoulder 14.

A pawl 15 is carried on the pinion 12, said pawl being pivoted on a screw or pin 105 16 which is permanently mounted on the pinion. The pawl acts to close or cover one of the key receptacles 13 in order to prevent the wrong key from entering the key receptacles and rotating the pinion 12. 110

The lower free and swinging extremity of the pawl 15 is angularly shaped or beveled. This beveled face of the pawl 15 corresponds to a bevel formed on the end of the 5 key which matches the lock, and as the key is inserted the corresponding bevels of the key and pawl engage and cause the pawl 15 to rotate about its center 16 to permit the key to pass into the receptacles 13 in 10 order to effect a turning movement of the pinion.

In order to subject the pawl to a positively normal closed position to cover one 15 of the key receptacles, it is necessary to employ a device to restrain the pawl to a normal forward position. This device comprises a guide 16', in which is slidably mounted a plunger 17. The plunger is fitted with a spring interposed between a plunger 20 head and a guide to throw the plunger forward against the pawl 15 and in engagement with the shoulder 14 which locks and prevents rotation of the pinion 12. This action holds the pawl in a closed 25 position over one of the key receptacles.

When the proper key is inserted in the lock, the corresponding angular face of the key and the pawl will engage to cause the pawl 15 to be displaced thus allowing the 30 key to enter the receptacles 13. In this way the key is engaged with the pinion, and the pinion may be rotated to move the bolt 7 rearwardly from extended and locked position.

35 A contact member 20 is fixed to the inside of the lock casing and insulated therefrom. An electric circuit line 21 connects with the contact member 20. The electric circuit 21 also connects with the metal casing of the 40 lock or is grounded thereto, and the circuit includes in series therewith a battery or other source of current and an alarm 22. The contact member is formed of an upstanding plate slightly spaced from the pawl 45 15, and is in such a position as to be contacted by the pawl 15 when a key is inserted in the lock which displaces the pawl 15.

A switch member or circuit closer element is associated with the lock to close a circuit 50 and ring the alarm should a burglar attempt to jimmy the door by inserting a prying tool between the lock and the door facing.

This circuit closer comprises an upstanding contact member 23 fixed to the lock casing, and an upstanding contact member 24. One 55 of the contactors projects through a hole formed in the lock casing and normally remains spaced from the other contactor. The contactor 24 should be made of spring material to restrain it from engagement with 60 the contactor 23. The contactor 23 is connected with the circuit 21 and insulated from the base while the contactor 24 is grounded on the base. In case a tool is inserted between the face of the lock and the 65 door facing the contactor 24 would press against the member 23 thereby closing the circuit 21 and ring the alarm 22.

The alarm would also be sounded when a key is inserted in the lock to displace the 70 pawl 15 as the said pawl would close the circuit 21 through the contact member 20. The alarm would be sounded in case the lock is tampered with, and would ring 75 whether the reprehensible person used a key or a prying tool.

This combination lock and alarm may be used to render a window or other opening 80 burglar proof to the same good and effect as it operates in connection with a door.

The invention is presented to fulfil the need felt for a burglar proof alarm safety lock of this nature.

Having thus described my invention, what I claim as new and desire to secure by Letters Patent is:

1. In a lock operated circuit closer of the character described, including a lock bolt, a pinion operating the lock bolt, a pawl pivoted on said pinion, and an electric contact member near said pawl adapted to be engaged by the same upon the operation of said pinion by a key.

2. In a lock operated circuit closer of the character described, a pinion rotatably mounted in the lock casing, a pin mounted on said pinion, a pawl pivoted on said pin, an upstanding plate slightly spaced from said pawl and forming a contact member adapted to be engaged by said pawl upon the 100 operation of said pinion by a key, substantially as described and for the purpose set forth.

ZYGMUNT H. PEHEL.
